APPARATUS FOR CRACKING OIL

Original Filed April 25, 1921

UNITED STATES PATENT OFFICE

GUSTAV EGLOFF AND HARRY P. BENNER, OF CHICAGO, ILLINOIS, ASSIGNEES TO
UNIVERSAL OIL PRODUCTS COMPANY, OF CHICAGO, ILLINOIS, A CORPORATION
OF SOUTH DAKOTA

APPARATUS FOR CRACKING OIL

Application filed April 25, 1921, Serial No. 484,368. Renewed September 28, 1928.

This invention relates to improvements in an apparatus for cracking oils and refers more particularly to an improved apparatus for facilitating the cracking reaction in the 5 vaporizing zone and in addition, distributing the carbon precipitated over the entire area of the expansion chamber.

Among the salient objects of the invention are to provide an apparatus for cracking oil 10 in which the oil, after being heated to a cracking temperature in the heating zone is passed through the transfer line and introduced into either or both ends of an expansion chamber; to provide an apparatus 15 whereby the oil when being introduced to the expansion chamber is fed through small orifice pipes or pipes of relatively smaller diameter than the main transfer line; to provide an apparatus which, by the introduction 20 of the heated oil to both sides of the expansion chamber, obviates, to a great extent, the present difficulty experienced in having the carbon accumulate at the outlet from the transfer line to the expansion chamber; to 25 provide an apparatus which is capable of more efficient operation, and longer operation; to provide an apparatus which produces a more even distribution of the carbon precipitated in the expansion chamber; and 30 in general to provide an improved apparatus of the character referred to.

The single figure in the drawing shows a view, partly in side elevation and partly in vertical section, of our improved apparatus.

It is well known that when cracking oils 35 at high temperatures and pressures, there is a decided tendency for precipitated carbon from the heated oil to build up and accumulate at the outlet from the transfer line in the vaporizing zone. This in time causes difficulties in that it eventually clogs up the outlet of the transfer line of the expansion chamber and makes it necessary to shut down the plant for cleaning. This localization 40 of carbon prevents efficient operation for a maximum period of time and it is one of the purposes of the present invention to eliminate, to a great extent, this localization of carbon in the expansion chamber, and at 45 the same time, assist in the vaporization of

the oil. By our improved process, due to the fact that we introduce the heated oil from the heating tubes through pipes of relatively smaller diameter than the main transfer line into either or both ends of the vapor 55 chamber, when carbon is precipitated, it is more evenly distributed and the tendency for the carbon to accumulate at the outlet of the transfer line is to a great extent obviated.

Referring in detail to the drawing, 1 designates the inlet line through which the raw oil to be treated is fed from any suitable source (not shown) by means of a pump 2. 3 designates the heating coils, which in the present instance take the form of a plurality 60 of tubes. 8 designates the furnace, provided with burner 9, and stack 11. After being heated to a cracking temperature in the heating coils, the oil passes by way of the transfer line 4, which terminates in two secondary transfer lines 5 and 6, in which are interposed the valves 7 and 7a, said secondary transfer lines communicating with either end of the vapor chamber 10, the latter preferably taking the form of an elongated shell-like chamber. If it is desired to introduce the heated oil into only one end of the expansion chamber, for instance the end nearest the heating coil, the valve 7 is closed and the valve 7a opened. On the other hand, 70 if it is desired to allow the heated oil to enter the expansion chamber at the opposite end, the valve 7a is closed, and the valve 7 opened. However, the particular application of our invention is the introduction of 80 the heated oil under treatment simultaneously into both ends of the expansion chamber through pipes of relatively smaller diameter than the main transfer line which, besides distributing the precipitated carbon 85 evenly, increases the velocity at which the oil is introduced to the vapor chamber. This latter method allows the expansion chamber to be used for a longer length of time than is now possible, due to the fact that the carbon is precipitated uniformly therein.

From the top of the vapor chamber extends a riser 12 leading to the bottom of a dephlegmator 13 through which the vapors released from the oil body in the expansion

chamber pass. The dephlegmator 13 is provided with baffles 14 around which the vapors must pass in their travel therethrough. The top of the riser 12 is equipped with the usual spaced cap portion 15, which allows the vapors to pass freely into the dephlegmator but preventing any of the reflux condensate from falling back into the expansion chamber. The drawoff line 16, controlled by valve 17, is provided at the bottom of the dephlegmator for returning the reflux condensate or condensed portions of the vapors to the charging line. After being dephlegmated, the vapors pass through the line 18, controlled by valve 19, into the water condenser coil 20 set in condenser box 21, where after being condensed, they are transferred by means of line 22 controlled by valve 23 into receiver 24. The receiver 24 is provided with the usual pressure gauge 25, liquid level gauge 26, liquid drawoff 27 controlled by valve 28 and gas outlet pipe 29 controlled by valve 30.

The operation of the process is as follows: The oil to be treated is introduced through the charging line 1 into the heating coils where it is heated to a temperature of between 700 and 800 degrees F. The heated oil, after passing through the heating tubes, is directed to the vapor chamber through the transfer line 4 and secondary lines 5 and 6, where it vaporizes, the vaporized portion passing into the dephlegmator and receiver as explained. The residuum or unvaporized oil is drawn off through the residuum outlet at the bottom of the vaporizing chamber. The system is at all times operated under a pressure of approximately 200 pounds to the square inch. By cracking a Mexican fuel oil of approximately 16 degrees Baumé in this manner, 25% of a distillate of gasoline-like character having a Baumé gravity between 51 and 55 degrees is obtained, based on the raw oil charge.

We claim as our invention:

In an apparatus for cracking oil, the combination with a furnace, of a cracking coil disposed therein through which oil is passed in a single passage to be subjected to a cracking temperature, an enlarged horizontal vapor chamber separated from said coil, of valve controlled means for passing heated oil in liquid phase from said coil into either of the opposite extremities of said horizontal vapor chamber, means for increasing the velocity of the oil as it reaches points near the entrances to said vapor chamber, a condenser in communication with the vapor chamber, and means for maintaining a superatmospheric pressure on the oil undergoing treatment.
